UNITED STATES PATENT OFFICE.

RUFUS G. STONE, OF GARDEN CITY, KANSAS.

TANK.

SPECIFICATION forming part of Letters Patent No. 728,037, dated May 12, 1903.

Application filed October 20, 1902. Serial No. 127,989. (No model.)

To all whom it may concern:

Be it known that I, RUFUS G. STONE, a citizen of the United States, residing at Garden City, in the county of Finney and State of Kansas, have invented a new and useful Tank, of which the following is a specification.

The invention relates to improvements in tanks.

The object of the present invention is to improve the construction of tanks and to increase their strength, durability, and efficiency, and to enable the same to be shipped in halves and nested together and assembled at their destination.

15 A further object of the invention is to provide a sheet-metal tank of this character in which there will be no seam at the angles or corner edges formed by the bottom and side walls.

20 The invention consists in the construction and novel combination and arrangement of parts hereinafter fully described, illustrated in the accompanying drawings, and pointed out in the claims hereto appended.

25 In the drawings, Figure 1 is a perspective view of a tank constructed in accordance with this invention. Fig. 2 is a similar view showing one-half of the tank. Fig. 3 is a horizontal sectional view.

30 Like numerals of reference designate corresponding parts in all the figures of the drawings.

1 designates a tank of hexagonal form; but it may be constructed of any other desired

35 polygonal form; and it consists of a bottom and side walls. The bottom and side walls are constructed of sheet metal, the bottom consisting of inner or central sections 2 and outer sections 3, which are extended and bent

40 at an angle to form wall-sections 4, thereby obviating the necessity of riveting or otherwise securing the bottom to the walls at the horizontal angle formed by such parts. The inner or central sections 2 are of semi-octagonal form riveted at their inner adjacent edges

45 and similarly secured at their outer edges to the adjacent ends of the outer sections 3, which are tapered and truncated, as illustrated in Fig. 3. The outer bottom sections

50 3 are riveted at their adjacent edges, and the wall-sections are secured together at their

vertical edges by rivets 5. The tank is designed to be constructed in halves, as illustrated in Fig. 2 of the accompanying drawings, to enable them to be nested and conveniently shipped, and in practice the rivets will be mounted at the seam edges to facilitate assembling the parts at their destination.

55 The upper edges of the wall-sections are bent outward to form projecting flanges 6 and 60 are secured to an outer frame 7, composed of bars having their ends 8 and 9 recessed at their opposite faces and overlapped and secured together. The upper and lower faces of the bars are flush, and the frame, which may be 65 constructed either of wood or metal, may be arranged on the exterior of the wall-sections, as illustrated in Figs. 1 and 2, or it may be located within the same.

70 By constructing and arranging the bottom and wall sections as illustrated in Figs. 1 and 2 of the drawings the rivets are arranged at points remote from the horizontal angles formed by the bottom and the walls, and seams at these angles are entirely dispensed 75 with, thereby greatly lessening the cost of construction and greatly increasing the strength and durability of a tank, and there is no liability of the parts separating at these angles or corners, as is the case with tanks 80 having seams at those parts; also, the parts may be assembled with much greater facility than is the case when the bottom and side walls are riveted at the angles formed by them.

85 It will be seen that the tank is simple and comparatively inexpensive in construction, that its cost of manufacture is greatly lessened by the particular arrangement of the parts and the seams at the adjacent edges of 90 the same, and that such arrangement also greatly facilitates assembling the parts. It will also be clear that the tank is adapted to be constructed in halves for nesting and shipping and that they may be readily assembled 95 at their destination.

What is claimed is—

1. A tank composed of a bottom section of polygonal form and side sections united thereto and to each other at their meeting edges, 100 said side sections comprising blanks having their longitudinal edges diverging from the

point of union with the bottom section to a predetermined common circumferential point and bent upward to form side walls.

2. A tank composed of inner and outer sections united at their meeting edges, the bottom being formed by the inner and outer sections conjointly, and the walls formed solely by the outer sections, said inner sections comprising blanks of polygonal form, and said 5 outer sections blanks having their longitudinal edges united to each other and diverging from the point of attachment with the inner sections to a predetermined common circumferential point and bent upward to form the 10 side walls.

15 3. A tank having inner bottom members of

polygonal form and side members each comprising a blank having its longitudinal edges parallel for a suitable portion of their length and then converging to form a truncated end 20 united to the bottom members, said side members being bent upward at the point of convergence of their edges to form side walls and having their meeting edges united.

In testimony that I claim the foregoing as 25 my own I have hereto affixed my signature in the presence of two witnesses.

RUFUS G. STONE.
